COIN CHUTE

Walter A. Tratsch and Bernhard C. Grunig, Chicago, Ill., assignors to A. B. T. Manufacturing Company, Chicago, Ill., a corporation of Illinois

Application April 20, 1936, Serial No. 75,252

6 Claims. (CL. 194—97)

This invention relates to a coin chute.

It is an object of this invention to provide an improved coin chute which is relatively simple and inexpensive in construction and efficient in use.

A further object of the present invention is to provide certain improvements upon the coin chute shown in our prior Patent No. 2,026,921 issued January 7, 1936.

10 It has been found, from experience in the art of coin chutes, that persons, and especially boys, who play coin-operated machines and devices, will often attempt to operate the coin chute of the same by fraudulently inserting a coin into 15 the coin aperture of the slide, then pushing the coin slide in far enough to operate the machine or device controlled thereby, and then retracting the coin and the slide, this being accomplished in a number of different ways, such as, for example, by attaching a string or analogous flexible element to the coin before inserting the same into the coin slide, whereupon, when the coin slide and the device, machine, or apparatus controlled thereby has been operated the player 25 will then pull back or retract the coin by means of the string. It has, therefore, been found to be possible to fraudulently operate the coin chute shown and described in our aforesaid patent, as well as other coin chutes, in this manner.

30 An additional object of the present invention, therefore, is to provide in the coin chute shown and described in the aforesaid patent a novel device for preventing fraudulent operation of the same in the manner hereinbefore described.

35 Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a top plan view of the coin chute shown and described in the aforesaid patent and having the present invention embodied there-

45 in;

Fig. 2 is a longitudinal sectional view on line 2—2 in Fig. 1;

Fig. 3 is a fragmentary bottom plan view taken on line 3—3 in Fig. 2;

50 Fig. 4 is a sectional detail view on line 4—4 in Fig. 1 showing certain of the parts in the position which they assume when the coin is dropping into the display pocket;

Fig. 5 is a bottom perspective detail view; and

55 Fig. 6 is a perspective view, partly in section,

showing the new dog which has been added to the coin chute of our above-identified patent.

A preferred form of the present invention is shown in the drawing, and is there shown, for the purpose of illustration, as associated with 5 the coin slide shown and described in our aforesaid patent, although it is to be understood that the present invention is not limited to use in connection with the coin chute shown and described in our aforesaid patent but may be used 10 with other types of coin chutes.

The coin chute shown in the accompanying drawing is therein generally indicated at 10, and includes a guide structure 11, and a coin slide 12 carried thereby; the guide structure 11 including a mounting or face plate 45 by means of which the coin chute 10 may be mounted in a wall of the cabinet or casing of a coin-controlled device, machine, or apparatus.

Provided in the coin slide 12 is a coin-receiving 20 aperture 27 and formed in the slide 12 at diametrically opposite points upon the periphery of the coin aperture 27 are depressed portions or teeth 38 and 39 (Fig. 2) which function to move the coin or token disposed in the coin aperture 27 in opposite directions, in a manner which is 25 well understood in the art.

Provided in the coin slide 12 is an elongated slot 21 (Fig. 2) and mounted in the guide structure 11 above the slide 12 is a stop 46 which includes a portion 41 that projects or extends downward to a point substantially in the same horizontal plane with the top surface of the coin slide 12 (Fig. 2).

The coin chute 10 includes latch dogs 35, 36 and 37 which are pivotally mounted on the guide structure 11 for engagement in the coin aperture 27 of the coin slide 12 so as to prevent operation of the coin slide 12 if no coin or token, or if a coin or token or slug having a thickness or diameter less than that of the intended coin or token, or if an apertured or slotted slug, or the like, is disposed in the coin aperture 27; this arrangement of the dogs 35, 36 and 37 and the function thereof being well known in the art.

40 Mounted on, or formed as a part of the upper wall of the guide structure 11, as may be desired, is an annular member or ring 13 in which is provided a coin displaying sight opening 14; and formed in the guide structure 11, below the slide 12, is a horizontal shelf 16. Likewise formed in the guide structure 11, below the coin slide 12 and adjacent the shelf 16, is a coin display pocket 17 (Fig. 2), this display pocket 17 being disposed 45 in registration with the sight opening 14.

45

50

55

55

Formed as an integral extension of the annular member 13 is a coin deflector 53 (Fig. 2).

A bracket or support 15 forms the bottom wall of the coin display pocket 17 (Fig. 2) and slidably mounted upon the bracket 15 below the coin display pocket 14-17 and below the shelf 16 is a slide bar 18 in which is provided a coin receiving aperture 19; and carried by this slide bar 18 and projecting upwardly therefrom, adjacent the inner end of the same, is a pin 20, this pin 20 projecting into the slot 21 which is formed in the coin slide 12.

Having one end attached to the slide bar 18, as at 22, and having its other end attached to the bottom wall 15 of the coin display pocket 14-17, as at 23, is a resetting spring 24 by means of which the slide bar 18 is normally urged (right to left, Figs. 1, 2 and 3) so as to dispose the coin discharge aperture 19 therein in registration with the coin display pocket 14-17; the slide bar 18 being stopped in this position by the engagement of its transverse edge 52 (Fig. 3) with a pair of bosses 25 and 26 which are formed on the bottom wall of the guide structure 11.

Provided in the coin slide 12 is a sight opening 28 (Fig. 2), and the coin slide 12 is normally urged (right to left, Fig. 6), by its resetting spring 47, so as to dispose the sight opening 28 formed therein in registration with the coin display or sight opening 14 which is formed in or upon the top wall of the guide structure 11.

Mounted on the guide structure 11, above the slide 12, is a magnet 42.

Having one end portion 29 attached to the annular member 13 and having its other end portion or arm 30 projecting downwardly through the coin display or sight opening 14 is a spring 31.

Pivotedly mounted on the guide structure 11, below the coin slide 12, as at 48, is a dog 50, and this dog 50 has an end portion 51 which projects upwardly (at one end of the depressed ledge or supporting wall 16), toward the slot 21 which is formed in the coin slide 12; the dog 50 being urged, by a spring 54 (Fig. 3), in a direction to project the upper end portion 51 thereof into the slot 21, for a reason to be explained presently.

Provided on the guide structure 11, above the coin slide 12, is a guard plate 55 which forms the subject matter of the applicants' copending application, Serial No. 43,152 filed October 2, 1935.

Operation

The coin slide 12 is normally disposed, by the action of the resetting spring 47, in coin-receiving position, with the sight opening 28 in the coin slide 12 disposed in registration with the sight opening 14, as in Figs. 1, 2 and 3, and when a coin is inserted into the coin aperture 27 of the coin slide 12 and the latter is pushed inwardly (left to right, Figs. 1, 2 and 3), the coin or token disposed in the coin aperture 27 of the slide 12 is carried by the slide 12 along the upper surface of the bottom wall 32 of the guide structure 11, and falls from the latter into the pocket, or onto the shelf 16, whereupon, upon further movement of the coin slide 12 the coin or token disposed in the coin aperture 27 of the coin slide 12 will be angled downwardly, by the deflector 53 (Fig. 4) off the front or inner end of the shelf 16. Further inward movement of the coin slide 12 and the slide bar 18 will then cause the coin or token to drop onto the upper surface of the rear portion 75 of the slide bar 18.

The coin or token is thus deposited on the upper surface of the slide bar 18, and as the coin slide 12 is pushed inwardly (left to right, Figs. 1, 2, and 3), the shoulder 33 formed in the coin slide 12 engages the pin 20, which is carried by the slide 18, whereupon the slide 12 and the slide 18 move together as a unit, and when the slides 12 and 18 are returned to their normal or initial positions the coin or token which has previously been deposited on the upper surface 10 of the lower slide 18 falls into the coin aperture 19 of the slide 18 wherein it is exposed to view through the registered sight openings 14 and 28.

A magnetic token or disc is prevented, by the coaction of the stop 41-46 and magnet 42, from entering the display pocket 14-17 since if a magnetic disc or token is inserted into the coin aperture 27 and the slide 12 is pushed inwardly the magnet 42 will hold the magnetic disc up in the plane of the coin slide 12 so that it will abut 20 the stop 41 and be prevented from falling onto the shelf 16.

The spring 31 retains a coin in the display pocket 14-17 and against dislodgment therefrom if the coin chute and associated apparatus are 25 shaken or inverted from their normal position, thereby preventing fraudulent dislodgment of the coin from the coin display pocket 14-17.

In the event that a person attempts to operate the coin chute fraudulently by attempting to 30 retract the coin from the display pocket 14-17, in any manner, as by attaching a string or analogous flexible article to the coin or token prior to inserting the coin or token into the coin aperture 27 of the slide 12 and pushing the latter inwardly, the coin thus sought to be retracted will be prevented, by the dog 50-51, (after it has been deposited in the display pocket 14-17) from being retracted or pulled back, since if an attempt is made to pull the coin back the same will bear 40 against the nose or upper end portion 51 of the dog 50 which projects into the slot 21. In this manner, fraudulent operation of the coin chute by retracting a coin therefrom is prevented.

While the dog 50 has been shown, for the 45 purpose of illustration, as associated with the coin chute shown and described in our aforesaid patent, it is to be understood that it may be used in conjunction with other types of coin chutes and is not limited to use with the visible display 50 type of coin chute shown and described in our aforesaid patent.

While we have illustrated and described the preferred form of construction for carrying our invention into effect, this is capable of variation 55 and modification, without departing from the spirit of the invention. We, therefore, do not wish to be limited to the precise details of construction set forth, but desire to avail ourselves of such variations and modifications as come within the 60 scope of the appended claims.

Having thus described our invention, what we claim as new and desire to protect by Letters Patent is:

1. A coin chute comprising a guide structure, 65 a coin slide carried by the said guide structure having a coin-receiving aperture formed therein and having an elongated slot formed therein, said guide structure including a wall disposed below the said coin slide for supporting a coin 70 in the said coin aperture of the same throughout at least a part of the inward movement or operative stroke of said coin slide, a stop member pivotally mounted on the said guide structure below the said coin slide and having a portion nor- 75

- 5 mally projecting upwardly into the said slot at one end of said supporting wall, and means normally urging the said member in a direction to project the said portion of said member into said slot at one end of said supporting wall whereby a coin inserted into the said coin aperture of said slide and moved by the latter along, and off from, the said supporting wall of said coin chute will be prevented from being retracted along said supporting wall by engagement with the said upwardly projecting portion of said member together with stationary means above said stop member and cooperable therewith to tilt a coin downwardly from said wall.
